UNITED STATES PATENT OFFICE.

THOMAS J. FEGLEY AND GEORGE O. LEOPOLD, OF PHILADELPHIA, PENNSYLVANIA,
ASSIGNORS TO NORTH BRO'S M'F'G CO., OF PHILADELPHIA, PENNSYLVANIA, A
CORPORATION OF PENNSYLVANIA.

HAND BRACE.

Application filed March 6, 1923. Serial No. 623,164.

To all whom it may concern:

Be it known that we, THOMAS J. FEGLEY and GEORGE O. LEOPOLD, citizens of the United States, residing in Philadelphia, 5 Pennsylvania, have invented certain Improvements in Hand Braces, of which the following is a specification.

One object of our invention is to improve the construction of the means for holding 10 the hand grip of a brace to the crank so that the grip will turn freely.

A further object of the invention is to construct the means so that the metal parts can be plated to improve the appearance 15 of the tool.

In the accompanying drawings:

Fig. 1 is a side view of a brace made in accordance with our invention;

Fig. 2. is an enlarged sectional view through 20 the hand grip; and

Fig. 3 is a detached perspective view of the sleeve and nuts.

Referring to the drawings, 1 is the crank member of the brace made of a metallic rod 25 bent into the shape shown. 2 is the hand grip. 3 is the hand hold mounted on the end 4. Located between a collar 5 on the end and the portion 6 of the hand hold is a ball bearing shown by dotted lines in 30 Fig. 1.

Secured to the opposite end 7 of the rod, which forms the crank, is a head 8, in which is located suitable ratchet mechanism controlled by a sliding shifter 9 so that the bit 35 can be actuated intermittently to the right or to the left, or a partial rotary movement of the brace may be obtained.

On the threaded stem 10, which extends 40 from the head 8, is a chuck 11 by which the bit is secured to the brace. The chuck can be of any type desired.

The present invention relates solely to the means for securing the hand hold in proper position.

12 designates a sleeve, which is sweated on 45 the straight portion 1^a of the crank. This sleeve has a screw thread at each end, as shown in Figs. 2 and 3. The hand hold 2 is mounted on the sleeve so as to turn freely thereon and is held from longitudinal movement by the nuts 13 and 14. Each nut has an internal flange 15, which rests against the end of the sleeve.

When the tool is being made, the portion 7 of the rod is straight, as shown by broken 55 lines in Fig. 1. The hand hold is not in place so that the upper portion of the brace can be nickel plated, after which the hand hold 2 and the lower nut are located in position and the portion 7 is bent to its final shape. 60 The upper nut is backed off and the hand hold 2 is pushed up to allow the lower portion of the rod forming the brace to be immersed in the plating bath.

When the plating is finished, the hand 65 hold is located in position on the sleeve and the nut 13 is screwed onto the sleeve. The head 8 is then attached to the crank and the other parts are assembled.

We claim:

1. The combination in a brace, of a rod forming the crank; a sleeve sweated upon the rod, said sleeve having a screw thread at each end; a hand hold mounted to turn freely on the sleeve; and nuts at each end 75 of the sleeve, said nuts preventing longitudinal movement of the hand hold.

2. The combination in a brace, of a rod bent to form a crank and having a straight portion; a sleeve secured to the straight portion, said sleeve having a screw thread at each end; a flanged nut on each end of the sleeve; and a hand hold mounted on the sleeve between the nuts, the flanges on the nuts bearing against the ends of the sleeve 80 and preventing binding of the hand hold.

THOMAS J. FEGLEY.
GEORGE O. LEOPOLD.
